DISPENSING CONTAINER AND BLANK WITH IMPROVED POURING MECHANISM

Carroll R. Alden, Detroit, Mich., assignor to Ex-Cell-O Corporation, Detroit, Mich., a corporation of Michigan

Application June 16, 1953, Serial No. 361,950

17 Claims. (Cl. 229—17)

The present invention relates generally to the packaging field. More specifically, the invention concerns a novel dispensing container and blank of bendable sheet material such as paperboard, finding particular, but not exclusive, utility when fabricated in a form commonly known as a "gable top." Such containers are particularly well adapted for the packaging of milk and other comestibles but may, of course, be employed for packaging a wide variety of fluent substances.

My copending U. S. applications, Serial No. 266,572, filed January 15, 1952, and Serial No. 269,785, filed February 4, 1952, and copending U. S. application Serial No. 321,217, filed November 18, 1952, by Francis E. Makuta, disclose dispensing containers having improved pouring characteristics and blanks for making such containers. Each of these containers has a pouring lip adjacent the pouring opening so as to prevent dribble during pouring and cut-off, irrespective of the fluid level in the container or the size or rate of flow of the poured stream.

The general aim of the present invention is to provide, in a container and blank having a dispensing means including a pouring lip, a pouring mechanism representing an improvement over the constructions disclosed in the foregoing applications.

A more specific object of the present invention is to provide a container and blank of the character set forth and which will include a novel arrangement for manipulating a pouring lip such as the one disclosed in Makuta application Serial No. 321,217, referred to above.

Another object is to provide a container and blank of the character set forth including structural features capable of implementing the objectives just recited but susceptible of economical manufacture at a cost comparing favorably with that required for paperboard containers presently available to the trade.

Other objects and advantages will become apparent from the following detailed description, taken together with the accompanying drawings in which:

Figure 1 is an enlarged fragmentary perspective view showing an illustrative container embodying the present invention and being in initially filled and sealed condition ready for use by the consumer.

Fig. 2 is a view similar to Fig. 1 but showing the container after its lift tab has been raised to expose the container pouring opening.

Fig. 3 is an enlarged fragmentary vertical section through the center of the container of Fig. 1 and displaying the pouring operation diagrammatically.

Fig. 4 is an enlarged fragmentary exploded perspective view detailing the pouring opening portion of the inside face of a blank from which the container of Fig. 1 may be formed.

Fig. 5 is an enlarged fragmentary plan view showing the pouring opening portion of the blank of Fig. 4 with the pouring opening ply in place thereon.

Fig. 6 is a view similar to Fig. 1 but showing a modified form of container also embodying the present invention.

2

Fig. 7 is a view similar to Fig. 2 but showing the modified container of Fig. 6 with its lift tab in raised position.

Figs. 8 and 9 are enlarged, fragmentary, vertical sectional views through the lift tab and pouring opening of the container shown in Fig. 6.

Fig. 10 is a fragmentary plan view showing the inside face of a blank from which the container of Fig. 6 may be fabricated.

Fig. 11 is an enlarged fragmentary plan view of the inside face of the blank of Fig. 10 showing the area of adhesive juncture but omitting the pouring opening ply.

Fig. 12 is a plan view detailing the pouring opening ply which attaches to the blank of Fig. 10.

Figs. 13 to 19, inclusive, are views similar to Figs. 6 to 12, respectively, but showing a further modified form of container and blank also embodying the invention.

While the invention is susceptible of various modifications and alternative constructions, certain illustrative embodiments have been shown in the drawings and will be described below in considerable detail. It should be understood, however, that there is no intention to limit the invention to the specific forms disclosed, but, on the contrary, the intention is to cover all modifications, alternative constructions and equivalents falling within the spirit and scope of the invention as expressed in the appended claims.

Referring more specifically to Figs. 1 to 5, inclusive, the invention is there exemplified in an illustrative container 20 and a container blank 20A from which the container 20 may be formed. The container 20, which will be recognized as a "gable top" container by those skilled in the art, and the blank 20A, may be manufactured from paperboard or other bendable sheet material. When erected, the container 20 is self-sustaining in shape and may be coated or impregnated with paraffin or some other appropriate substance to make it moistureproof and capable of holding fluids such as milk. In this instance, the container 20 comprises a tubular body 21 of approximately square or rectangular cross section and having a top end closure 22 surmounted by a central laminar rib 24. The container body 21 also has a bottom end closure (not shown) of any suitable form, the details of the bottom closure constituting no part of the present invention. Flanking the laminar rib 24, the top end closure 22 has a pair of inclined roof panels 25, 26. The latter respectively adjoin front and rear body panels 28, 29 along a common score line 30 which separates the top closure 22 from the container body 21.

The contents of the container 20 may be dispensed through a suitable pouring opening in one of the roof panels 25, 26. In this instance, the roof panel 25 is provided with a sanitarily protected pouring opening 31 initially covered by a lift tab 32 (Figs. 1 and 2). The pouring opening 31 is cut into a pouring opening ply 34 of sheet stock bonded to the inside face of the roof panel 25 and the body panel 28. The pouring opening 31 and the sanitarily protected margins thereof are initially covered by the lift tab 32, becoming exposed upon elevation of the latter by the user. The lift tab 32 in this case is integral with the roof panel 25 and the body panel 28, being defined therein by means of a pair of spaced apart severance lines 35, 36 which terminate at their lower ends in a finger recess 38. A reclosure plug 39, defined in the pouring opening ply 34 by the incisions 40, 41, 42 which also define the pouring opening 31, is bonded to the inner face of the lift tab 32. Thus the reclosure plug 39 for all intents and purposes actually behaves as an integral part of the lift tab 32 and is movable with it. After initial opening of the container, if the lift tab 32 be moved to its closed position, the plug 39 simply snaps into its original position in the pour-

ing opening 31 and the frictional effect between the perimeter of the plug 39 and the opening 31 serves yieldably to maintain the lift tab 32 in closed position.

In order to give the container 20 dribble-free pouring and cut-off characteristics, the container 20 is formed with a manipulable pouring lip 44 adjacent the pouring opening 31, after the manner disclosed in Makuta application Serial No. 321,217 mentioned earlier herein. In this case, the lip 44 is integral with the pouring opening ply 34 and has at least three edges defined in the stock of the ply 34 by perforating, pre-cutting or equivalent operations. The lip 44 is hingedly connected to the ply 34 along a fold or hinge line 43 and initially occupies a dormant position in the plane of the ply 34. Upon elevation of the lift tab 32, the pouring lip 44 becomes accessible to the user and can readily be downfolded or reversely bent about the line 43 to a fully operative position wherein its free edge overhangs the finger recess 38 and the face of the underlying body panel 28 (Figs. 2 and 3). In this position, the free lower edge 45 of the pouring lip 44 constitutes a separation edge spaced from the plane of the underlying body panel 28. This separation edge eliminates adhesion and dribble during pouring and cut-off as explained in my co-pending applications Serial No. 266,572 and Serial No. 269,785, as well as in Makuta application Serial No. 321,217, *supra*.

Provision is made in the construction of the blank 20A and the container 20 so that the pouring lip 44 will be displaced automatically as an incident to raising the lift tab 32 during initial opening of the container. This is accomplished by the use of a severable connection between the lift tab 32 and the pouring lip 44, such connection being situated at a point spaced from the respective hinge lines of both the lip 44 and the tab 32.

In the present instance, the foregoing is accomplished by means of at least one severable tie 46 of paperboard stock which is left in the pouring opening ply 34 between the free edge 45 of the pouring lip and the complementary adjacent edge of the reclosure plug 39. As indicated in Figs. 1, 2, 4 and 5, the tie 46 is situated near the midpoint of the incision line 41 and interrupts the same. With this arrangement, initial elevation of the lift tab 32 toward its fully open position produces a resulting upward angular movement of the pouring lip 44 about its hinge line 43, the stress in the tie 46 increasing sharply as elevation of the lift tab 32 progresses. Eventually, the tie 46 severs under this stress, permitting the lift tab 32 to be fully elevated by the user and leaving the pouring lip 44 in an upstanding condition out of the plane of the pouring opening ply 34, as indicated in Fig. 2. While the angular distance through which the pouring lip 44 has moved may be insufficient to effect full realization of the good pouring qualities of which the container 20 is capable, such movement will be sufficient to remind the user that good pouring may be more fully achieved by urging the pouring lip 44 to its fully downfolded position about its hinge line 43, such position being shown in Fig. 3.

Reclosure of the pouring opening may be effected regardless of whether the pouring lip 44 is in its fully downfolded position or has been returned manually to approximately its original dormant position because in either event the reclosure plug 39 will frictionally engage a substantial portion of the perimeter of the pouring opening 31.

Turning now to Figs. 4 and 5, certain details of the blank 20A are there shown. In this instance, it will be noted that the pouring opening ply 34 constitutes a separate patch 48 having a transverse score line 49. The patch 48 also has defined therein the reclosure plug 39 and the pouring lip 44 as well as the connecting tie 46. The main portion of the blank 20A, on the other hand, has the lift tab 32 and the finger recess 38 already defined therein. After the main portion of the blank has been cut and scored, the

pouring opening patch 48 is bonded to the inside faces of the panels 25, 28 by means of an adhesive juncture 50 surrounding the lift tab 32. The juncture 50 includes an extension 51 which bonds the reclosure plug 39 to the inside face of the lift tab 32. The patch 48 is laterally centered on the panels 25, 28 and positioned with its score line 49 coinciding substantially with the transverse score line 30 of the blank, as illustrated in Fig. 5.

A container embodying the present invention may be fully prepared for pouring in two simple steps. First, the pouring opening 31 is exposed by grasping the lower end of the lift tab 32 and pulling up on the same until the pouring opening 31 is completely exposed, as indicated in Fig. 2. This automatically displaces the pouring lip 44 out of its dormant position. Second, the pouring lip 44 is then downfolded about the line 43 from its displaced position into its operative position as shown in Fig. 3. This may be accomplished by grasping the lip 44 either with the fingers or by the use of any other suitable means for bending the lip 44 the remainder of the way toward its fully downfolded position. Pouring may thereupon be effectively accomplished by inclining the container to the desired angle.

Referring next to Figs. 6 to 12, inclusive, there is shown a modified form of container 120 and a blank 120A which also illustratively embody the present invention. In general, the container 120 and blank 120A are similar to the container 20 and blank 20A described earlier herein. Thus the container 120 comprises a tubular body 121 having a top end closure 122 surmounted by a central rib 124. Flanking the rib 124 are a pair of inclined roof panels 125, 126 which respectively adjoin front and rear body panels 128, 129 along common score line 130 which separates the top closure 122 from the body 121. The roof panel 125 has a sanitarily protected pouring opening 131 initially covered by a lift tab 132. (Figs. 6 and 7). The pouring opening 131 is formed in a pouring opening ply 134 fixed to the inside face of the roof panel 125 and the body panel 128. The lift tab 132 in this instance is also integral with the roof panel 125 and the extreme upper portion of the body panel 128 but is substantially shorter, being defined by spaced apart severance lines 135, 136 which terminate approximately at the score line 130 and intersect the ends of an incision line 138 in the upper portion of the body panel 128. This construction results in a lift tab which has a slightly protruding end portion overhanging the body panel 128, the entire lift tab being substantially coplanar with the inclined roof panel 125.

As indicated in Figs. 6, 7, 10 and 12, the pouring opening ply 134 in this instance happens to be fashioned as a separate patch 140 similar to the one shown in Alden application Serial No. 269,785, *supra*. The pouring opening 131 is formed as a notch adjacent the upper end of the patch 140 and the latter is fixed in centered relation on the inside faces of the panels 125, 128 with its transverse score line 141 coinciding substantially with the score line 130 on the blank 120A. Attachment of the patch 140 to the blank is effected by means of a substantially U-shaped adhesive juncture 142.

The pouring opening ply 134 has a pouring lip 144 generally similar to the pouring lip 44 of the container 20. The lip 144 has a free separation edge 145 and a pair of lateral edges 146 defined by incisions in the ply 134. Like the lip 44 of the container 20, the pouring lip 144 is initially situated in a dormant position coplanar with the pouring opening ply 134.

Provision is made in the blank 120A and in the container 120 for displacing the pouring lip 144 automatically as an incident to raising the lift tab 132 during initial opening of the container. As in the container 20, this is accomplished by the use of a severable connection between the lift tab 132 and the pouring lip 144 situated at a point spaced from the respective hinge lines of both the lip 144 and the lift tab 132. In this instance, however, the severable connection comprises a rupturable adhesive juncture 148 (Figs. 6, 7, 8 and 9) between the inside face of the lift

tab 132 and the initially abutting face of the pouring lip 144. The juncture 148 may take a variety of shapes and in this particular case happens to be of circular form, being produced as by means of a small circular adhesive coated area 148A on the inside face of the blank 120A (Fig. 11). When the pouring opening patch 140 is affixed to the inside face of the blank 120A, the adhesive area 148A registers with a corresponding circular area on the pouring lip 144 and designated by the numeral 148B (Fig. 12). By reason of the construction just described, initial elevation of the lift tab 132 from the closed position represented in Fig. 8 toward its fully open position as indicated in Fig. 7 produces a resulting upward angular movement of the pouring lip 144 about its hinge line 143. As lifting of the tab 132 progresses, stress builds up in the adhesive juncture 148 until the connection between the lift tab 132 and the pouring lip 144 ruptures completely. This permits the lift tab 132 to be elevated from the position of Fig. 9 to its fully elevated position indicated in Fig. 7 and leaves the pouring lip 144 in an upstanding condition out of the plane of the pouring opening ply 134. The user is therewith reminded to complete the downfolding of the pouring lip 144 prior to pouring from the container 120.

Figs. 13 to 19, inclusive, illustrate another modified container and blank 220, 220A also embodying the invention. Since the container 220 and the blank 220A are somewhat similar to the other embodiments of the invention already described above, it will be unnecessary at this point to present a detailed description of their common features. Suffice it to say that the container 220 includes a roof panel 225 and an underlying body panel 228 adjacent thereto. The roof panel 225 serves as a pouring opening panel, being provided with a pouring opening 231 and an overlying lift tab 232. The pouring opening 231 is formed as an aperture in a pouring opening ply 234, the latter, in turn, being defined by a pouring patch 240. The patch 240 is adhesively bonded to the inside faces of the panels 225 and 228, the transverse score line 241 of the patch 240 coinciding substantially with the main transverse score line 230 of the blank and which separates the container body from the top closure. The pouring opening ply 234 has a manipulable pouring lip 244 initially disposed in a dormant position adjacent the pouring opening 231 and coplanar with the ply 234. The pouring lip 244 is generally similar to the pouring lips 44 and 144 of the containers described earlier herein but is situated somewhat lower in ply 234 and hinges substantially about the transverse score line 241 in the latter. In this instance, there is no reclosure plug associated with the pouring opening or the lift tab although such a feature may optionally be included in the container 220 if desired.

Automatic displacement of the pouring lip 244 incident to initial raising of the lift tab 232 is accomplished in a manner similar to that utilized in the container 120. Thus, there is interposed between the inner face of the lift tab 232 and the abutting face of the pouring lip 244 an adhesive juncture 248 (Figures 13 to 16) which is ultimately rupturable as the lift tab 232 becomes progressively elevated. While the juncture 248 may assume a variety of patterns, it happens to be circular in this instance and occupies the area 248A on the lift tab 232 and the area 248B on the pouring lip 244, these areas being in registration when the patch 240 is applied to the inner face of the blank 220A. In operation and usage, the container 220 behaves much as the other forms of containers previously described. However, it might be noted that when the pouring lip 244 is in its fully downturned position, its free edge overhangs the underlying body panel 228 to a substantially greater extent than the free edges of the pouring lips 44 and 144.

I claim as my invention:

1. A container of paperboard or the like and comprising, in combination, a pouring opening panel and a wall panel, said panels being angularly disposed relative to each other and connected by a common score line, a

lift tab severably attached to said pouring opening panel and having its major portion coplanar therewith, a pouring opening ply fixed in abutting relation with the inner faces of said pouring opening panel and said wall panel, said pouring opening ply having defined therein a pouring opening and a manipulable pouring lip adjacent said pouring opening, said pouring lip being initially disposed in a dormant position coplanar with said pouring opening ply, said pouring lip also having a downturned fully operative position with its free edge overhanging said wall panel, and a frangible connection between said pouring lip and said lift tab, said connection being constructed and arranged to rupture during initial elevation of said lift tab and after said pouring lip has been moved from its dormant position partially toward its downturned operative position.

2. In a dispensing gable top container, the combination comprising an inclined roof panel, an underlying body panel adjacent said roof panel, a lift tab defined in both said panels but having its major portion lying in said roof panel and having a hinge line connection therewith, a pouring opening patch adhesively secured to the inner faces of said roof panel and said body panel, means defining in said pouring opening panel a pouring opening and a manipulable pouring lip adjacent the latter, said pouring lip having a free edge and a pair of lateral edges and being initially disposed in dormant position coplanar with said patch, said pouring lip having a hinge line connection with said patch and being susceptible of being reversely

bent by the user into an active position with its free edge spaced from said body panel but overhanging the general plane thereof, and a rupturable connection between said lift tab and said pouring lip, said connection being spaced from the respective hinge lines of said lift tab and said pouring lip.

3. In a cut and scored blank for a dispensing gable top container, the combination comprising a roof panel, a body panel adjacent said roof panel, a lift tab defined in both said panels but having its major portion lying in said

roof panel and having a hinge line connection therewith, a pouring opening patch adhesively secured to the inner faces of said roof panel and said body panel, means defining in said pouring opening panel a pouring opening and a manipulable pouring lip adjacent the latter, said pouring lip having a free edge and a pair of lateral edges and being initially disposed in dormant position coplanar with said patch, said pouring lip having a hinge line connection with said patch, and a rupturable connection between said lift tab and said pouring lip, said connection being spaced from the respective hinge lines of said lift tab and said pouring lip.

4. In a container of paperboard or the like, the combination comprising a ply having a pouring opening therein, a pouring lip initially coplanar with said pouring opening ply and situated adjacent said pouring opening, said pouring lip being hinged to said pouring opening ply, a lift tab disposed in overlying relation with said pouring opening, and means for severably attaching said pouring lip to said lift tab whereby angularly displacement of said

pouring lip is effected as an incident to raising of said lift tab.

5. A container of bendable sheet material such as paperboard having a pouring opening with an overlying lift tab and a pouring lip adjacent said pouring opening, said container being characterized by a severable connection between said lift tab and said pouring lip whereby the latter becomes displaced as an incident to elevation of said lift tab.

6. In a cut and scored blank for a container of paperboard or the like, the combination comprising a ply having a pouring opening therein, a pouring lip coplanar with said pouring opening ply and situated adjacent said pouring opening, said pouring lip being hingedly attached to said pouring opening ply, a lift tab disposed in over-

lying relation with said pouring opening, and a severable connection between said pouring lip and said lift tab.

7. A container of bendable sheet material such as paperboard having a pouring opening with an overlying lift tab and a downturnable pouring lip in dormant position adjacent said pouring opening, said container being characterized by means for severably connecting said lift tab and said pouring lip whereby the latter becomes displaced and partially turned down as an incident to elevation of said lift tab.

8. In a container of paperboard or the like, the combination comprising a pouring opening panel including a ply having a pouring opening therein, a pouring lip coplanar with said pouring opening ply and situated adjacent said pouring opening, said pouring lip being integral with and hinged to said pouring opening ply, a reclosure plug in said pouring opening ply complementary with said pouring opening, and a severable tie of stock connecting said pouring lip to said reclosure plug.

9. In a container of paperboard or the like, the combination of a pouring opening panel including a ply having a pouring opening therein, a pouring lip coplanar with said pouring opening ply and situated adjacent said pouring opening, said pouring lip being hinged to said pouring opening ply, a reclosure plug in said pouring opening ply substantially complementary with said pouring opening, a lift tab disposed in overlying relation with said pouring opening, a permanent connection between said lift tab and said reclosure plug, and a frangible connection between said reclosure plug and said pouring lip whereby angular displacement of said pouring lip is effected as an incident to raising of said lift tab.

10. A container of paperboard or the like and comprising, in combination, a pouring opening panel and a wall panel, said panels being angularly disposed relative to each other and connected by a common score line, a lift tab severally attached to said pouring opening panel and having its major portion coplanar therewith, a pouring opening patch fixed in abutting relation with the inner faces of said pouring opening panel and said wall panel, said pouring opening patch having defined therein a pouring opening and a manipulable pouring lip adjacent said pouring opening, said pouring lip being initially disposed in a dormant position coplanar with said pouring opening patch, a reclosure plug in said pouring opening patch, a permanent adhesive juncture between said reclosure plug and said lift tab, and a rupturable tie of stock connecting said reclosure plug and said pouring lip, said tie being constructed and arranged to rupture during initial elevation of said lift tab and after said pouring lip has been angularly moved from its dormant position toward its downturned operative position.

11. In a blank for a dispensing container of paperboard or the like, the combination of a pouring opening panel including a ply having a pouring opening therein, a pouring lip coplanar with said pouring opening ply and situated adjacent said pouring opening, said pouring lip being hinged to said pouring opening ply, a reclosure plug in said pouring opening ply substantially complementary with said pouring opening, a lift tab disposed in overlying relation with said pouring opening, a permanent adhesive juncture between said lift tab and said reclosure plug, and a frangible connection of paperboard stock between said reclosure plug and said pouring lip.

12. In a blank for a dispensing gable top container, the combination comprising a roof panel, a body panel adjacent said roof panel, a lift tab defined in both said panels but having its major portion lying in said roof panel and having a hinge line connection therewith, a pouring opening patch adhesively secured to the inner faces of said roof panel and said body panel, means defining in said pouring opening panel a pouring opening and a reclosure plug and a manipulable pouring lip adjacent the pouring opening, said pouring lip having a free

edge and a pair of lateral edges and being disposed in dormant position coplanar with said patch, said pouring lip also having a hinge line connection with said patch, a permanent connection between said reclosure plug and said lift tab, and a rupturable tie of stock connecting said reclosure plug and the free edge of said pouring lip, said tie being spaced from the respective hinge lines of said lift tab and said pouring lip.

13. A container of bendable sheet material such as paperboard having a pouring opening with an overlying lift tab and a downturnable pouring lip adjacent said pouring opening, said container being characterized by a severable tie of paperboard stock connecting said lift tab and said pouring lip whereby the latter becomes displaced as an incident to elevation of said lift tab.

14. A container of bendable sheet material such as paperboard having a pouring opening with an overlying lift tab and a downturnable pouring lip adjacent said pouring opening, said container being characterized by a rupturable adhesive juncture between said lift tab and said pouring lip whereby the latter becomes displaced as an incident to elevation of said lift tab.

15. In a dispensing container of paperboard or the like, the combination comprising a pouring opening panel and a wall panel, said panels being angularly disposed relative to each other and connected by a common score line, a lift tab severally attached to said pouring opening panel and having its major portion coplanar therewith, a pouring opening patch fixed in abutting relation with the inner faces of said pouring opening panel and said wall panel, said pouring opening patch having defined therein a pouring opening and a manipulable pouring lip adjacent said pouring opening, said pouring lip being initially disposed in a dormant position coplanar with said pouring opening patch, and a severable adhesive juncture between said pouring lip and the inner face of said lift tab, said juncture being constructed and arranged to rupture during initial elevation of said lift tab and after said pouring lip has been angularly removed from its dormant position toward its downturned operative position.

16. In a dispensing gable top container, the combination comprising an inclined roof panel, an underlying body panel adjacent said roof panel, a lift tab defined in both said side panels but having its major portion lying in said roof panel, a pouring opening patch adhesively secured to the inner faces of said roof panel and said body panel, a notch adjacent one edge of said pouring opening patch and defining a pouring opening therein, a manipulable pouring lip defined in said patch adjacent one edge of said pouring opening, said pouring lip having a free edge and a pair of lateral edges and being initially disposed in dormant position coplanar with said patch, said pouring lip having a hinge line connection with said patch and being susceptible of being reversely bent by the user into an active position with its free edge spaced from said body panel but overhanging the general plane thereof, and a rupturable adhesive juncture between the inner face of said lift tab and said pouring lip.

17. In a dispensing gable top container, the combination comprising an inclined roof panel, an underlying body panel adjacent said roof panel and separated therefrom by a common score line, a lift tab defined in both said side panels but having its major portion lying in said roof panel, a pouring opening patch having a transverse score line and adhesively secured to the inner faces of said roof panel and said body panel with said transverse score line coinciding substantially with said common score line, means defining in said pouring opening patch a pouring opening and a manipulable pouring lip adjacent the latter, said pouring lip having a free edge and a pair of lateral edges and being initially disposed in dormant position coplanar with said patch, said pouring

lip being hingedly connected with said patch substantially on said transverse score line and being susceptible of being reversely bent by the user into an active position with its free edge spaced from said body panel but overhanging the general plane thereof, and a rupturable adhesive juncture between the inside face of said lift tab and the abutting face of said pouring lip.
